UNITED STATES PATENT OFFICE

WALTER EVERETT MOLINS AND JOHN WALKER CHALMERS, OF LONDON, ENGLAND

LABELING MACHINERY

Application filed November 8, 1929, Serial No. 405,800, and in Great Britain November 28, 1929.

This invention is for improvements in or relating to machinery for applying labels to packages, and more particularly to a machine adapted to fold a label of paper about a box or like container, for example, a package of tobacco so as to completely envelop the same around four sides thereof, leaving two sides of the package unprotected.

The present invention consists of a machine for applying labels to packages wherein a series of spaced packages are arranged to be fed in rapid succession into engagement with a web of material arranged to be severed into strips as the packages meet the same, means arranged to provide the said material with adhesive and means arranged to move a package together with a strip of material through mechanism operable to wrap the material around the package and secure the two ends of the same to the package.

The invention will be more particularly described with reference to the accompanying drawings, in which:—

Fig. 1 shows a side elevation of a machine constructed according to this invention.

Figs. 2, 3 and 4 show successive stages of one method of automatically folding a label around a box.

Figs. 5 and 6 show similar diagrams of a second method of automatically folding the label about a box.

Fig. 7 shows a third method of folding a label around a box.

Figure 8 is a diagrammatic illustration of a gum supplying device applicable to the arrangement shown in Figure 5 of the drawings.

Figure 9 shows a mechanical movement applicable to the arrangement disclosed in Fig. 7, and

Figure 10 illustrates a sheet feeding mechanism for carrying out the labeling method described herein in the event that separate sheets rather than a continuous web of labeling material is supplied.

Referring to Fig. 1, a series of boxes 1 are arranged in a vertical magazine 2 in such a manner that the lowermost box is removed from the magazine by a pusher piece 3

mounted on an endless conveyor 4 and arranged to automatically move the box along the bed 5 of the machine and into engagement with a web of paper 6. The paper web 6 is fed from a reel so as to pass through a printing mechanism 8 over a heater 9 arranged to dry the ink, and around a series of guide rollers 10. The paper then passes through a gumming unit 11 which applies gum on the non-printed side of the label in a series of lines for example, three.

The gumming unit is also constructed so as to leave an ungummed portion at predetermined points upon the web in order to permit the web to be severed at these points without the cutters becoming coated with gum.

The web of paper then passes through cutting mechanism 12 which is arranged to sever the paper as the box meets the web, whereafter the box and the web are carried beneath a plate 13 which is adapted to fold the strip about the box so that one end of the strip protrudes from the rear end of the box in the manner shown in Fig. 2.

Gum is then applied to the end of the label and the bottom of the box by means of an oscillating roller 13a which receives gum from a roller 14 rotating in a gum bath (see Fig. 3) or if necessary, the gum may be applied to the free end of the label.

The box is then raised into a stacker 15 in the manner shown in Figs. 2 and 3, and the free end of the strip is folded downwardly so as to leave a portion protruding from the underside of the box, whereupon the next oncoming box folds the protruding strip on to the underside of the box so that the strip completely envelops the same (see Fig. 4).

In the modified form of folding shown in Figs. 5 and 6, the box is arranged to meet the label at about mid-way of its length so that the label is formed into a U shape with two over hanging portions at the rear of the package as shown in Fig. 5. When the package reaches the vertical stacker the bottom overlapping flap is folded upwardly by an oscillating tucker 16, which may, if necessary, apply gum to the flap, and the top flap is folded down over the lower one as the pack-

age is pushed upwardly into the stacker 15.

One arrangement by means of which gum may be supplied to the tucker 16 is shown in Figure 8 of the drawings. It will be observed from this figure that a lever 16d carrying a gum applying roller 16a is oscillated by means of a cam 16e and the two cams shown in this figure are rotated in timed relation so that gum is supplied to the tucker 16 while it occupies a lower position away from the package.

In another way of carrying the invention into effect, the package is arranged to meet the web of material immediately after the latter commences to pass through the slot in the bed of the machine, and the long overhanging strip which is produced, is folded by rotating the package through a semi-circle during which motion the long flap is folded around the box. An apparatus for this purpose is shown in Fig. 7, and on reference to that figure it will be seen that after the folding operation the package is moved into a compartment 17 formed in a rotary member 18, and when the package has reached the position shown in Fig. 7 the member 18 is rotated through a semi-circle, during which movement the over hanging flap is bent down by a plate 19. The member 18 may be rotated intermittently by any of the various types of mechanical movements commonly used for such a purpose. One such arrangement is illustrated in Figure 9 of the drawings in which the shaft 18h on which the member 18 is mounted carries a gear 18a which is in turn driven by a gear 18b. The latter gear is formed integrally with or is secured to a slotted disc 18c. A second disc 18e carries a roller 18d which is arranged to engage in the slots formed in the plate 18c so that on each rotation of the disc 18e the slotted disc 18c will be rotated through approximately 60°. The disc 18e is preferably provided with a cam shaped periphery having a cam rise at the point 18f. A roller 18i carried on a lever 18g is urged into contact with the periphery of the disc 18e by means of a spring 18j having one end attached to the lever and the other end to any convenient portion of the machine. A second roller 18k carried at one end of the lever 18g is thus caused to engage and disengage with the slots in the plate 18c, thus locking the plate against rotation when it is not being positively driven by the roller 18d. It will be observed that the cam rise 18f is so positioned with relation to the roller 18d that one of these rollers is withdrawn from the slotted plate 18c as the other roller moves into engagement with the plate.

When the package reaches the upper position it is removed from the compartment by a pusher 20 carried on a continuous conveyor 21, and during this movement the long flap is folded smoothly down upon the pack-

age by a plate 22. The completely wrapped package is then thrust upwards into the magazine.

The gum may be applied to the ends of the label at any convenient point during the operation, or if necessary, sufficient gum may be applied by the apparatus 11 to hold the label in place.

Thus it will be seen that according to the present invention there is provided a composite machine which may be employed to wrap a printed label around a box of cigarettes or like package.

It will be appreciated that instead of the web of paper being printed as it is fed through the machine, the same may be pre-printed and provided with suitable holes whereby the pre-printed web may be fed into the path of the boxes, or if necessary, cut sheets may be fed from a magazine.

One form of mechanism suitable for feeding cut sheets is illustrated in Figure 10 of the drawings. In this figure the sheets 23 are shown as stacked in a magazine 24 and an oscillating suction tube 25 pivoted at 26 serves to pull the forward end of the sheets downwardly, one at a time. The suction tube may be oscillated in any convenient manner, for instance by means of the lever 27 and link 28 from a suitable cam, not shown.

A roller 29 is carried on a lever 30 which is integral with the lever 27, the arrangement being such that as the front edge of the sheet is pulled downwardly onto a continuously rotating roller 31 the roller 29 rocks 100 into contact with the upper surface of the blank which is then fed by the roller 31 into engagement with the rollers 32.

A cooperating roller 33 deflects the sheet vertically downwards through guides 34 and 105 the bed slot 35. A support roller 36 serves to carry the forward ends of the sheets.

What we claim as our invention and desire to secure by Letters Patent is:—

1. In a machine for applying labels to packages, the combination with means for continuously feeding a series of spaced packages in succession through a predetermined path, means for feeding labeling material across the path of movement of said packages, whereby each successive package is caused to engage and carry therewith the material to be applied thereto, means for applying adhesive to the material, and mechanism arranged adjacent the path of movement of the packages and associated material for wrapping the material about each package.

2. In a machine for applying labels to packages, the combination with means for continuously feeding a series of spaced packages in succession through a predetermined path, means for feeding labeling material across the path of movement of said packages, whereby each successive package is 130

- caused to engage and carry therewith the material to be applied thereto, means for applying adhesive to the material, and stationary means arranged adjacent the path of movement of said packages for engaging the material and wrapping the same about the associated package.
3. in a machine for applying labels to packages, the combination with means for continuously feeding a series of spaced packages in succession through a predetermined path, means for feeding labeling material across the path of movement of said packages, whereby each successive package is caused to engage and carry therewith the material to be applied thereto, means for applying adhesive to the material, and means arranged adjacent the path of movement of said packages for wrapping said material about each package and pressing the same against four sides thereof and against the other end of the wrapping material to cause the material to completely encompass the package.
6. In a machine for applying labels to substantially rectangular packages, the combination with means for continuously feeding a series of spaced packages in succession through a predetermined path, means for feeding labeling material across the path of movement of said packages, whereby each successive package is caused to engage and carry therewith the material to be applied thereto, means for applying adhesive to the material, and means arranged adjacent the path of movement of said packages for wrapping said material about each package and pressing the same against four sides thereof.
7. In a machine for applying labels to substantially rectangular packages, the combination with means for continuously feeding a series of spaced packages in succession through a predetermined path, means for feeding labeling material across the path of movement of said packages, whereby each successive package is caused to engage and carry therewith the material to be applied thereto, said material being of such length and so positioned at the time of engagement of the package therewith that the two ends of the material project outwardly of the leading side of the package, one to a greater extent, and one to a lesser extent than the length of the sides of the package intermediate the leading and rearward sides thereof, means for pressing the material upon the said intermediate sides of the package into substantially U form with the longer end trailing, and means for folding the trailing end upon the rearward side of the package.
4. In a machine for applying labels to substantially rectangular packages, the combination with means for continuously feeding a series of spaced packages in succession through a predetermined path, means for feeding labeling material across the path of movement of said packages, whereby each successive package is caused to engage and carry therewith the material to be applied thereto, means for applying adhesive to the material, and means arranged adjacent the path of movement of said packages for wrapping said material about each package and pressing the same against four sides thereof.
8. In a machine for applying labels to substantially rectangular packages, the combination with means for continuously feeding a series of spaced packages in succession through a predetermined path, means for feeding labeling material across the path of movement of said packages, whereby each successive package is caused to engage and carry therewith the material to be applied thereto, said material being of such length and so positioned at the time of engagement of the package therewith that the two ends of the material project outwardly of the leading side of the package, one to a greater extent, and one to a lesser extent than the length of the sides of the package intermediate the leading and rearward sides thereof, means for pressing the material upon the said intermediate sides of the package into substantially U form with the longer end trailing, and means for folding the trailing end upon the rearward side of the package, said last named means including mechanism for moving each package transversely of the said path of movement, whereby the succeeding package may engage the trailing end and press the same against four sides thereof.
5. In a machine for applying labels to substantially rectangular packages, the combination with means for continuously feeding a series of spaced packages in succession through a predetermined path, means for feeding labeling material across the path of movement of said packages, whereby each successive package is caused to engage and carry therewith the material to be applied thereto, means for applying adhesive to the material, means arranged adjacent the path of movement of said packages for wrapping said material about each package and pressing the same against four sides thereof in such manner as to leave a trailing end of the material extending outwardly of the rearward side of the package, and means for shifting each package transversely of the said path of movement to position the package with the trailing end of the material intercepting the said path of movement, whereby the succeeding package may engage and press the said trailing end against the package.
6. In a machine for applying labels to substantially rectangular packages, the combination with means for continuously feeding a series of spaced packages in succession through a predetermined path, means for feeding labeling material across the path of movement of said packages, whereby each successive package is caused to engage and carry therewith the material to be applied thereto, means for applying adhesive to the material, and means arranged adjacent the path of movement of said packages for wrapping said material about each package and pressing the same against four sides thereof and against the other end of the wrapping material to cause the material to completely encompass the package.
7. In a machine for applying labels to substantially rectangular packages, the combination with means for continuously feeding a series of spaced packages in succession through a predetermined path, means for feeding labeling material across the path of movement of said packages, whereby each successive package is caused to engage and carry therewith the material to be applied thereto, said material being of such length and so positioned at the time of engagement of the package therewith that the two ends of the material project outwardly of the leading side of the package, one to a greater extent, and one to a lesser extent than the length of the sides of the package intermediate the leading and rearward sides thereof, means for pressing the material upon the said intermediate sides of the package into substantially U form with the longer end trailing, and means for folding the trailing end upon the rearward side of the package.
8. In a machine for applying labels to substantially rectangular packages, the combination with means for continuously feeding a series of spaced packages in succession through a predetermined path, means for feeding labeling material across the path of movement of said packages, whereby each successive package is caused to engage and carry therewith the material to be applied thereto, said material being of such length and so positioned at the time of engagement of the package therewith that the two ends of the material project outwardly of the leading side of the package, one to a greater extent, and one to a lesser extent than the length of the sides of the package intermediate the leading and rearward sides thereof, means for pressing the material upon the said intermediate sides of the package into substantially U form with the longer end trailing, and means for folding the trailing end upon the rearward side of the package, said last named means including mechanism for moving each package transversely of the said path of movement, whereby the succeeding package may engage the trailing end and press the same against four sides thereof.

same against the adjacent intermediate side of the package.

9. In a machine for applying labels to substantially rectangular packages, the combination with means for continuously feeding a series of spaced packages in succession through a predetermined path, means for feeding labeling material across the path of movement of said packages, whereby each successive package is caused to engage and carry therewith the material to be applied thereto, said material being of such length and so positioned at the time of engagement of the package therewith that the two ends of the material project outwardly of the leading side of the package to a greater extent than the length of the sides of the package intermediate the leading and rearward sides thereof, means for folding the material about the package into substantially U form with both ends thereof trailing, means for pressing one of said trailing ends against the rearward side of the package, and means including mechanism for shifting each package transversely to fold the remaining trailing end of the material against the rearward side of the package.

10. In a machine for applying labels to substantially rectangular packages, the combination with means for continuously feeding a series of spaced packages in succession through a predetermined path, means for feeding labeling material across the path of movement of said packages, whereby each successive package is caused to engage and carry therewith the material to be applied thereto, said material being of such length and so positioned at the time of engagement of the package therewith that the two ends of the material project outwardly of the leading side of the package to a greater extent than the length of the sides of the package intermediate the leading and rearward sides thereof, means for folding the material about the package into substantially U form with both ends thereof trailing, means for pressing one of said trailing ends against the rearward side of the package, a stacker extending transversely of the path of movement of said packages, and means for thrusting each package into said stacker to fold the remaining trailing end of the material against the rearward side of the package.

11. In a machine for applying labels to packages the combination with means for continuously feeding a series of spaced packages in succession through a predetermined path, means for feeding labeling material across the path of movement of said packages, whereby each successive package is caused to engage and carry therewith the material to be applied thereto, a carrier rotatable about an axis transverse to the said path of movement for receiving the packages and associated material, and stationary means en-

gaging a trailing end of the material during rotation of the carrier to wrap the material about the package.

12. In a machine for applying labels to substantially rectangular packages, the combination with means for continuously feeding a series of spaced packages in succession through a predetermined path, means for feeding labeling material across the path of movement of said packages, whereby each successive package is caused to engage and carry therewith the material to be applied thereto, said material being of such length and so positioned at the time of engagement of the package therewith that the two ends of the material project outwardly of the leading side of the package, one to a greater extent, and one to a lesser extent than the length of the sides of the package intermediate the leading and rearward sides thereof, means for pressing the material upon the said intermediate sides of the package into substantially U form with the longer end trailing, means for folding the trailing end upon the rearward side of the package, said last named means including a carrier rotatable about an axis transverse to the said path of movement for receiving the packages and associated material, and stationary means engaging the trailing end of the material during rotation of the carrier to wrap the said end about the package.

In testimony whereof we hereunto affix our signatures.
